BY

Martin O. Smith
ATTORNEY.

UNITED STATES PATENT OFFICE

2,261,450

WRENCH

Clarence L. Pritchett, Huntington Park, Calif.

Application February 26, 1940, Serial No. 320,784

3 Claims. (Cl. 81—106)

My invention relates to wrenches of the general type disclosed in U. S. Letters Patent No. 504,698 issued September 12, 1893; No. 1,570,627 issued January 26, 1926; and No. 1,728,282 issued September 17, 1929.

The principal objects of my invention are, to generally improve upon and simplify the construction of wrenches of the type disclosed in the above mentioned patents and to provide a quick acting wrench that may be easily and quickly adjusted so as to fit the nuts, pipes and other parts that are engaged by the jaws of the wrench and further, to provide a wrench of the character referred to that shall be simple in construction, strong and durable, comparatively light in weight and inexpensive of manufacture.

A further object of my invention is, to provide a wrench that will not become clogged and inoperative as a result of rust and the accumulation of foreign substances such as dirt and congealed grease and oil upon the movable parts of the wrench and which objectionable conditions are very frequently found in wrenches of the type forming the subject matter of the above mentioned patents.

A further object of my invention is, to provide a wrench having the general shape and appearance of a conventional pipe wrench and which will also function effectively as a monkey wrench and/or, angle or crescent headed wrenches having one fixed and one movable jaw.

With the foregoing and other objects in view, my invention consists in certain novel features of construction and arrangement of parts that will be hereinafter more fully described and claimed and illustrated in the accompanying drawing in which:

Fig. 1 is a perspective view of a wrench constructed in accordance with my invention.

Fig. 2 is a side elevational view of the forward portion of the wrench with parts thereof in vertical section.

Fig. 3 is a vertical cross section taken on the line 3—3 of Fig. 2.

Fig. 4 is an enlarged cross section taken on the line 4—4 of Fig. 2.

Fig. 5 is an enlarged cross section taken on the line 5—5 of Fig. 2.

Fig. 6 is a perspective view of a strap that is mounted for sliding movement on the wrench handle and which carries the movable jaw.

Fig. 7 is a perspective view of a nut that is associated with the movable jaw carrying strap.

Fig. 8 is a perspective view of a modified form 55

of the nut used in connection with the strap that carries the movable jaw.

Referring by numerals to the accompanying drawing which illustrates a preferred embodiment of my invention, 10, 10 designate the parallel legs of the wrench handle, which legs are preferably formed in a single piece from a metal rod or bar either round or polygonal in cross section and which is bent double or, said handle may be stamped or cast in a single piece from suitable metal.

Rigidly fixed by means of rivets or in any suitable manner to the forward ends of the legs 10 of the handle is a jaw 11 having a work engaging face 12 that is preferably ribbed or corrugated and which, if desired, may be slightly inclined with respect to the major axis of the handle.

Mounted for longitudinal sliding movement on the members 10 forming the handle is a substantially U-shaped strap of metal, the free ends 15 of said strap terminating above the uppermost one of the legs 10 and passing through the free ends of this strap is a pin or rivet 14.

The rear end portion of a hood 15 that is of inverted U-shape in cross section is positioned between the upwardly projecting end portions of the strap 13 and rivet 14 is rigidly seated in the rear portions of the side walls of this hood. Pivoted on the pin or rivet 14 between the side 20 walls of hood 15 is the inner end of a short shank 16 that overlies the upper one of the legs 10 of the wrench handle and the forward end of this shank is extended downward and shaped to form a jaw 17 having a ribbed or corrugated face 18 25 that opposes the corrugated face 12 on fixed jaw 11.

A portion of the rear end of shank 16 or that end that is pivoted in the rear portion of the hood 15 is cut away to form a notch 19 and 30 positioned in said notch and bearing on the under face of the upper rear portion of the hood 15 is an expansive spring 20 which yieldingly resists downward movement of the sliding jaw 17.

Under normal conditions spring 20 maintains 35 the upper face of shank 16 against the under side of the top of hood 15 and when so positioned, the under face of said shank is spaced a slight distance above the upper end of fixed jaw 11 so that when the wrench is engaged on a tube 40 or rod, the movable jaw 17 may swing downward a short distance on its axis, the rivet 14, after the manner of a conventional pipe wrench.

The upper portions of the legs of strap 13 are extended a short distance forwardly of the front edges of the lower portions of said legs in order

to provide shoulders 13a which when the strap carrying the shank 16 and sliding jaw 17 is moved forward to its limit of movement, engage the sides of the upper rear portion of the fixed jaw 11 and thus, the lower portions of the legs of the strap are spaced apart from the lower portion of said jaw 11 so as to eliminate any tendency of strains imparted to the sliding jaw to impart tilting movement to the strap 13 and to the fixed jaw 11 while the upper portions of the legs of said strap are in engagement with the upper portion of said fixed jaw.

Formed on the inner faces of the legs of strap 13 just below those portions of the legs that receive the hood 15 and rear portion of shank 16 are inwardly presented lugs 21 that co-operate to provide a bearing for the upper one of the legs 10 of the wrench handle during the sliding movement of the strap upon said handle.

In order to reduce friction between the parts during sliding movement thereof and to provide clearance for dirt, congealed oil, grease, or the like, the curved faces of the lugs 21 that provide bearings for the upper member of the wrench handle are provided with longitudinally disposed grooves 22. Practically this same construction is employed at the lower end of the strap 13 for the lower member 10 of the handle, but instead of providing lugs such as 21, the entire lower end of the yoke 13 is increased in thickness and the inner curved face of thickened portion which engages the lower leg of the handle is provided with longitudinally disposed grooves 23.

In the construction of the strap or yoke 13, I prefer to form the same from malleable cast metal in order to enable the legs of the strap to be spread apart during the assembly of the parts of the wrench and then by pressure forcing said legs into parallel arrangement before the rivet 14 is set and headed.

A trunnion 24 is formed on the rear end of a threaded rod that occupies a position between the legs 10 of the handle and said trunnion has bearing in that portion of the rod that connects the rear ends of the members 10 of the handle and the forward end of said threaded rod bears directly against the rear face of fixed jaw 11.

This screw rod is preferably formed in a single piece and has its forward portion provided with a buttress thread 26, the flat face of which is rearwardly presented and the rear portion of said rod is provided with a double V thread 27.

In order to impart rotary motion to the screw rod, a nut 28 is mounted on that portion of said rod having the double V thread 27 and formed in the top and bottom of said nut are grooves 29 for the reception of the members 10 of the handle. The outer side faces of nut 28 are provided with vertically disposed ribs 30 or said surfaces may be milled or corrugated in order to enable the nut to be more firmly engaged by the thumb and fingers of the operator's hand.

The double V thread 27 may be cut on the rear portion of the rod or, if desired, the rear portion of the rod when manufactured may be substantially diamond shape in cross section and then twisted so as to produce the double thread.

In order to transmit rotary motion of the threaded shaft to the strap 13 that carries the sliding jaw, a nut 31 is mounted on the portion of the rod having the buttress thread 26 and said nut being located between the members 10 of the handle and between the sides of the strap

13. Formed in the top and bottom of this nut are grooves 32 for the accommodation of the members 10 of the handle and formed in the faces of said grooves 32 are smaller grooves 33 which materially reduces the area of the bearing surfaces between the members 10 and the nut.

In order to retain the nut 31 in operative position between the side members of strap 13, lugs 34 are formed integral with and project inwardly from the inner faces of the side walls of the strap and said lugs engage in corresponding recesses 35 that are formed in the side faces of nut 31.

In some instances, the nut 31 may be dispensed with and threads for the reception of the buttress thread 26 may be stamped or formed on the inner faces of the side walls of the strap 13.

As illustrated in Fig. 2, the straight shoulder on the buttress thread is rearwardly presented, which construction is particularly applicable in pipe wrenches, but for monkey wrenches the flat face or shoulder on the thread should be forwardly presented.

Further in some instances, it may be found desirable to form the double V thread on the opening through nut 28 and with grooves formed on the rear portion of the rotating rod, which arrangement is the reverse of that illustrated in Fig. 2.

In the manipulation of my improved wrench, the sliding or movable jaw 17 may be quickly adjusted toward or away from fixed jaw 11 by engaging the nut 28 between the thumb and index finger and moving said nut along the members 10 of the handle, thereby imparting quick rotary movement to the threaded shaft with the result that the buttress thread engaging nut 31 will move the latter, the yoke 13, together with hood 15, shank 16 and jaw 17, lengthwise upon the handle so that the work may be received between the jaws 11 and 17.

The particularly advantageous features of my improved construction are, the quick acting adjustment of the movable jaw, the simplicity of manufacture and assembly of the entire wrench and particularly the strap or yoke that carries the sliding jaw and the grooving of the strap and the nut 31 so as to minimize friction of the sliding parts and the minimizing of tendency of clogging of the sliding parts due to accumulations of rust, dirt, congealed grease, oil, and the like.

Thus it will be seen that I have provided a wrench that is relatively simple in construction, inexpensive of manufacture and very effective in performing the functions for which it is intended.

In my improved wrench, it is to be noted that the U-shaped strap or yoke which is formed of malleable metal is capable of being easily and quickly applied to the wrench handle and that the shank 16 that carries the movable jaw 17 is extended over the fixed jaw 11 and connected to the upper portion of the yoke or strap, thereby eliminating time, labor and consequent expense that would otherwise be involved if the fixed jaw 11 were extended upwardly and provided with a square hole for the reception of the shank and which construction is found in a number of wrenches of the type to which my invention relates.

In Fig. 8 I have illustrated a modified form of the nut that is utilized with the strap 13 that carries the movable jaw 17.

This form of nut is formed from a single piece of strap metal bent to form a substantially rec-

tangular loop 36 open at its sides and provided in its opposite end walls with openings 37 that engage the double V thread 27 on the rod that carries the movable jaw 11.

It will be understood that minor changes in the size, form and construction of the various parts of my improved wrench, may be made and substituted for those herein shown and described, without departing from the spirit of my invention, the scope of which is set forth in the appended claims.

I claim as my invention:

1. In a wrench, a handle comprising parallel members integrally connected at one end, a jaw secured to the opposite end of said handle, a rod mounted for rotation on said handle and arranged between the parallel portions thereof, a quick acting thread formed on a portion of said rod, a nut arranged for sliding movement between the parallel portions of the handle and provided with a threaded opening for the reception of that portion of the rod having the quick acting thread, those portions of the nut that engage the parallel portions of the rod being provided with grooves that are disposed parallel with each other and with the axes of the parallel rods, a substantially U-shaped strap arranged for sliding movement on said handle, a shank pivotally connected to one end of said U-shaped strap, a jaw carried by said shank and disposed opposite the fixed jaw on said handle, a nut carried by said strap and disposed between the parallel portions of said handle and a thread formed on said rod in advance of said quick acting thread for engaging the nut carried by said strap.

2. A wrench as set forth in claim 1, with bearings formed on said strap for engaging the par-

allel portions of said handle and said bearings being provided with grooves that are disposed parallel to the axes of the parallel portions of said handle.

3. In a wrench, a handle comprising parallel members integrally connected at one end, a jaw mounted on the opposite ends of said parallel members, a rod mounted for rotation between said parallel members, the ends of which rod bear respectively on the integrally connected ends of said parallel members and upon the rear face of the jaw carried by said members, a thread formed on the forward portion of said rod, a quick acting thread formed on the rear portion of said rod, a yoke mounted for sliding movement on said parallel members, grooved bearings formed on said yoke for said parallel members the faces of which grooved bearings are provided with grooves that are disposed parallel with each other and parallel with the handle members, a hood secured to the upper end of said yoke, a shank pivoted to the upper portion of said yoke and having its rear portion disposed within said hood, a jaw on the forward end of said shank, which jaw opposes the jaw carried by said parallel members, an expansive spring interposed between the rear portion of said shank and said hood, a nut mounted on that portion of the rod having the quick acting thread and having sliding engagement with the parallel members of the handle and the faces of said nut that have sliding engagement with the parallel members of the handle being provided with longitudinally disposed grooves that are parallel with each other and with the parallel members of the handle.

CLARENCE L. PRITCHETT.
